G. T. FIELDING.
ILLUMINATING DEVICE.
APPLICATION FILED JULY 29, 1913.

1,105,414.

Patented July 28, 1914

UNITED STATES PATENT OFFICE.

GEORGE T. FIELDING, OF NEW YORK, N. Y.

ILLUMINATING DEVICE.

1,105,414.

Specification of Letters Patent.

Patented July 28, 1914.

Application filed July 29, 1913. Serial No. 781,802.

To all whom it may concern:

Be it known that I, GEORGE T. FIELDING, a citizen of the United States, and a resident of the city of New York, borough of the Bronx, in the county and State of New York, have invented a new and Improved Illuminating Device, of which the following is a full, clear, and exact description.

The object of the invention is to provide 10 a new and improved illuminating device more especially designed as an advertising medium for use in the show windows of drug stores, perfumery stores and the like, and which forms an attraction for passersby.

In order to accomplish the desired result use is made of a vessel or bottle of diaphanous material and containing a fluid, a series of lights arranged in the rear of the 20 said vessel, differently colored media between the said lights and the rear of the said vessel, and means causing intermittent turning of the said lights whereby the rays of light emanating from the said light are 25 refracted by the fluid in the said vessel, and the said fluid appears in rapid succession in the various colors of the said media and in the various colors produced by the blending of the colors of the said media.

30 A practical embodiment of the invention is represented in the accompanying drawings forming a part of this specification, in which similar characters of reference indicate corresponding parts in all the views.

35 Figure 1 is a side elevation of the illuminating device with the casing shown in section; Fig. 2 is a front face view of the casing and the incandescent electric lamps mounted therein; Fig. 3 is a sectional plan 40 view of the illuminating device on the line 3—3 of Fig. 1 and Fig. 4 is an enlarged sectional plan view of the automatic electric switch for each incandescent electric lamp.

A vessel or bottle A of glass or other suitable diaphanous material and of ovoid or other ornamental shape is mounted on the top and bottom in caps B and B' rigidly connected with each other by rods B². The top cap B is suspended by chains C or the 50 like from a suitable overhead support arranged in a window casing or other structure in which the illuminating device is to be displayed. The vessel A is filled with a fluid preferably water or other liquid rendered somewhat cloudy by the addition of a 55 suitable substance such as dissolved soap to

retard the refraction of the light. The rear portion of the vessel A is provided with means E for the diffusion of light, the said means consisting preferably of a coating of paint of white or other color. The two rear connecting rods B² of the mounting are engaged by lugs F' of a casing F arranged in the rear of the rear portion of the vessel A, and the said casing F is open at the front 55 and is in contact at the sides, top and bottom with the vessel A.

Within the casing F is arranged a series of lamps G, G', G², preferably incandescent electric lamps having their sockets attached to the top of the casing F so that the lamps are suspended within the casing one alongside the other. The lamps G, G' and G² are located in close proximity to the rear portion of the vessel A so that the rays of light 75 emanating from the said lamps are refracted by the liquid D contained in the vessel A, the said liquid being illuminated uniformly owing to the rays of light being diffused in their passage through the diffusing means E 80 on the rear portion of the vessel A. The electric lamps G, G' and G² are provided with bulbs of different colors such as red, green and blue, as indicated in the drawings. Each of the electric lamps G, G' and G² is 85 provided with an automatic electric switch for periodically flashing each lamp, the said switch being preferably of the construction shown and described in the Letters Patent of the United States, No. 884,514, granted to 90 Andrew H. Miller, on April 14, 1908, and which lamps are now in the market. As shown in Fig. 4, the automatic electric switch consists essentially of a heater a which actuates the thermo-dynamic switch b, the lamp filament being indicated by c.

The back of the casing F is provided with a suitable door F² to permit access to the interior of the said casing for placing the electric lamps in position or removing the same therefrom whenever it is deemed necessary to do so. The top of the casing F is provided with vent holes F³ to allow circulation of air through the casing to keep the same and the vessel A as cool as possible. 105 The interior surface of the casing F is preferably nickel plated to form a reflecting surface.

When the illuminating device is in use and the electric lamps G, G' and G² are 110 burning then the rays of light emanating intermittently from the lamps are refracted

by the fluid D in the vessel A and consequently the said fluid appears in rapid succession in the various colors of the bulbs and in the various colors produced by the blending of the colors of the said bulbs. Thus at one time the fluid D may appear momentarily green, at another time red and at another time blue, according to which of the lamps G, G' and G² is burning, while the others are extinguished; and at another time the liquid may appear in any blended color according to which of the two lamps are burning, or in case all three are burning at the time. As the changes from one color to another are in rapid succession it is evident that a very attractive display is had.

It is understood that by the arrangement described different colored media are interposed between the vessel A and the corresponding sources of light, and means are employed to cause the intermittent burning of the lights to produce the desired effect, which is heightened by a proper diffusion of the rays of light through the diffusing means E.

Although the vessel A is shown and described as being suspended it is evident that it may be otherwise supported in any desired place.

Having thus described my invention, I claim as new and desire to secure by Letters Patent:

1. In an illuminating device, the combination of a vessel of diaphanous material, a cloudy liquid filling the said vessel, a series of lights adapted to be intermittently burned and arranged in the rear of the said vessel, differently colored media between the said lights and the rear of the said vessel, whereby the refraction of the rays of light emanating from the said lights is retarded by the cloudy particles in the said fluid, and the said cloudy fluid appears in rapid succession in the various colors of the said media and in the various colors produced by the blending of the colors of the said media.

2. In an illuminating device, the combination of a vessel of diaphanous material, a liquid contained in the said vessel and

rendered cloudy by the addition of a substance tending to retard the refraction of light through the said liquid, a casing held on the rear of the vessel and having an open front into which extends the rear of the said vessel, a series of incandescent electric lamps arranged in the said casing one along side the other, the said electric lamps having differently-colored bulbs and the said electric lamps being adapted to be intermittently burned to produce irregular flashing of the lamp lights, the refraction of the rays of light emanating from the said lamps being retarded by the retarding substance in the liquid, the latter appearing in rapid succession in the various colors of the bulbs and in the various colors produced by the blending of the said bulb colors.

3. In an illuminating device, the combination of a vessel of diaphanous material, a liquid contained in the said vessel and rendered cloudy by the addition of a substance and tending to retard the refraction of light through the said liquid, a casing held on the rear of the vessel and having an open front into which extends the rear of the said vessel, means for removably fastening the casing in position on the said vessel, a series of incandescent electric lamps arranged in the said casing one along side the other, the said electric lamps having differently colored bulbs, the colors being primary colors, the said electric lamps being adapted to be intermittently burned to produce irregular flashing of the lamp lights, the refraction of the rays of light emanating from the said lamp being retarded by the retarding substance in the liquid, the latter appearing in rapid succession in the various colors of the bulbs and in the various colors produced by the blending of the said bulb colors.

In testimony whereof I have signed my name to this specification in the presence of two subscribing witnesses.

GEORGE T. FIELDING.
